(57) **CLAIM**

The ornamental design for a tumbler as shown and described.

DESCRIPTION

FIG. 1 is a top perspective view of a tumbler showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top perspective view thereof in an alternate condition;

FIG. 9 is a right side elevation view thereof;

FIG. 10 is a left side elevation view thereof;

FIG. 11 is a front elevation view thereof;

FIG. 12 is a rear elevation view thereof;

FIG. 13 is a top plan view thereof; and,

FIG. 14 is a bottom plan view.

The broken lines are shown for the purpose of illustrating both parts of the tumbler as well as exemplary environmental subject matter. None of the broken lines form part of the claimed design.

1 Claim, 8 Drawing Sheets
